UNITED STATES PATENT OFFICE.

JAMES R. KEARNEY AND HARRY L. JOHNSON, OF KANSAS CITY, MISSOURI.

WALL BRACKET.

Application filed December 16, 1920. Serial No. 431,140.

To all whom it may concern:

Be it known that we, JAMES R. KEARNEY, and HARRY L. JOHNSON, citizens of the United States, residing at Kansas City, Missouri, have invented a certain new and useful Improvement in Wall Brackets, of which the following is a full, clear, and exact description, such as will enable others skilled in the art to which it appertains to make and use the same, reference being had to the accompanying drawings, forming part of this specification, in which—

Figure 1 is a detail view of our improved wall bracket.

Figure 1^a is a detail view of a modified form of wedge.

Figure 2 is a sectional view showing the same in position.

This invention relates to a new and useful improvement in wall brackets, especially designed for use with brick or stone walls, the object being to construct a device of the character described which is simple and cheap and one which can be readily and quickly applied so that when in position it can not be easily displaced or removed.

The bracket is intended to support electric insulators or electrical appliances, but it is obvious that it can be used for other purposes; and in this connection it is apparent that the projecting end of the bracket may be shaped differently from that shown in the drawing so that it is more readily adapted for various devices which it is intended to support.

In the drawings, 1 and 2 indicate flexible tongues which are preferably more widely separated at their free ends than toward their heel portions. These tongues may be pointed at their ends, but we prefer to make them slightly blunt, and by use of a roughening tool provide their outer faces near their ends with burrs or holding projections 3. The tongues are scored or cut, as at 4, so as to form flaring wings 5 which are bent upwardly and forwardly, said wings being yielding to such an extent that when they enter between two bricks or pieces of stone, as shown in Figure 2, they will engage the contiguous surfaces thereof and assist in preventing the bracket from being withdrawn, and also tend to prevent vertical and lateral movement of the wedge near the outer edge or face of the brick.

Abutting tongues 6 are also struck up from the body portion of the bracket and

near its outer end, these abutting tongues extending in opposite directions so that they will engage the outer faces of the bricks or stones on each side of the crevice in which the bracket is driven. The head portion of the bracket, or that portion which extends outwardly beyond the faces of the bricks or stones and which is used to support a device or appliance (not shown) is preferably formed by folding the blank, from which the bracket is made, upon itself. This head portion 7, shown in the drawings as a shelf, may be provided with an opening or openings 8 for the purpose of attaching a supported object thereon.

In practice, the mortar between the stones or bricks is first removed to the required depth. When a proper opening is made, a wedge 9 is placed between the free ends of the tongues 1 and the tongues introduced into the opening and driven home. The wedge in striking the bottom of the opening formed to receive it is arrested and further driving of the bracket inwardly over the wedge will cause the tongues to spread apart, as shown in Figure 2, and their roughened outer faces to engage the mortar, stones or bricks with which they come in contact. It is always necessary that the wedge reach the bottom of the opening made to receive the bracket. With the wedge inserted between the tongues of a bracket, the hammer blows on the outer end of the bracket will act on the wedge and draw the same in between the tongues as the bracket is being driven home. The final driving movement of the bracket will force the flexible flaring wings inwardly, as shown in Figure 2, and this will also assist in preventing withdrawal of the bracket and vertical and lateral movement thereof. The opening for the bracket is preferably made deep enough so that the abutting tongues can be brought into engagement with the faces of the bricks or stones between which the bracket is driven.

It is obvious that the bracket can be arranged either in a vertical or horizontal position depending upon the direction of the crevices from which the mortar or cement between the bricks or stones is removed.

Wedge 9 is preferably made of frangible material, such as a gray iron casting, and is provided with transversely disposed grooves 10 across its face whereby in applying the device, if it is found that the opening made to receive the tongues of the

bracket is not of sufficient size to permit the bracket to be driven home so that its abutments will engage the outer face of the wall, then the operator can shorten the wedge by breaking off one or more sections from its larger end.

In Figure 1^a we have shown a wedge produced by pressing or stamping corrugations 10^a in the wedge, these corrugations increasing in depth from the flat point of the wedge to the opposite end thereof. If it is found that the opening made to receive the tongues of the bracket is not of sufficient size to permit the bracket to be driven home, so that its abutments will engage the outer face of the wall, then the operator can thin the wedge 10 by hammering out the corrugations.

What we claim is:

- 20 1. A wall bracket formed of a single flat piece of metal bent upon itself at its outer end and having flat inwardly extending tongues whose free ends are flared, said flared free ends being provided with roughened outer surfaces to engage the wall into which the bracket is driven.
- 25 2. A wall bracket formed of a single flat piece of metal bent upon itself to form a flat outwardly projecting shelf-like extension located outside of the wall in which the bracket is mounted, the inner ends of said bracket which are located within the wall terminating in flat flexible diverging tongues, and a flat wedge arranged within 30 the opening in the wall, said wedge being designed to enter between and spread the tongues apart when the bracket is driven home.
- 35 3. A wall bracket formed of a single flat piece of metal bent upon itself at one end,

the free ends of said bracket terminating in flexible tongues which are slightly divergent, and wings struck up from the bases of said tongues, said wings flaring in a direction opposite the angles of inclination of 45 said tongues, respectively.

4. A wall bracket having flexible tongues, flaring wings located at the bases of said tongues and abutments located on said bracket outside of or beyond said flaring 50 wings and which abutments are designed to engage the outer faces of the wall.

5. A wall bracket comprising a pair of slightly diverging flat flexible tongues, an outward extension forming a flat shelf-like 55 continuation of said tongues and providing a support adjacent the outer face of the wall, and a flat wedge located in an opening in the wall and designed to enter between and spread the tongues when the 60 bracket is driven home.

6. A wall bracket comprising an outer shelf-like extension designed to be located outside of the wall in which the bracket is mounted, inwardly extending flexible 65 tongues designed to be located within an opening in the wall, abutments at the inner edges of said shelf-like extension and which are designed to engage the outer face of the wall, and flaring wings on said tongues 70 and removed from the free ends thereof, said wings being designed to engage the wall and assist in preventing removal of the bracket from the opening therein.

In testimony whereof we hereunto affix 75 our signatures this second day of December, 1920.

JAMES R. KEARNEY.
HARRY L. JOHNSON.
